(57) **CLAIM**

I claim the ornamental design for an outsole for a shoe, as shown and described.

DESCRIPTION

FIG. 1 is a bottom view of an outsole for a shoe showing my new design;

FIG. 2 is a right side view thereof;

FIG. 3 is a left side view thereof;

FIG. 4 is a front view thereof;

FIG. 5 is a rear view thereof; and,

FIG. 6 is an enlarged perspective view of the area labeled “6” in FIG. 1.

The broken line showing a curved shape in the arch area of FIG. 1, along with the parallel broken lines around the peripheries of FIGS. 2–5, represent the boundaries of the design; with neither the lines themselves, nor the areas within them forming any part of the claim.

Although the heel is shown in detail in FIG. 6, it is understood that the forepart of the outsole for a shoe has the same texture.
